(57) CLAIM

The ornamental design for a sofa, swivel chair, and chair set, as shown and described.

DESCRIPTION

FIG. 1 is a perspective view of a sofa, swivel chair, and chair set combined state, consisting of a chair, a swivel chair, and a sofa, showing my new design;

FIG. 2 is a rear perspective view thereof of its combined state;

FIG. 3 is a front perspective view of the chair component of the sofa, swivel chair, and chair set of FIG. 1, shown separately to reveal aspects of the design that may not be apparent in other views;

FIG. 4 is a rear perspective view thereof;

FIG. 5 is a front view thereof;

FIG. 6 is a rear view thereof;

FIG. 7 is a left side view thereof;

FIG. 8 is a right view thereof;

FIG. 9 is a top view thereof;

FIG. 10 is a bottom view thereof;

FIG. 11 is a front perspective view of the swivel chair component of the sofa, swivel chair, and chair set of FIG. 1, shown separately to reveal aspects of the design that may not be apparent in other views;

FIG. 12 is a rear perspective view thereof;

FIG. 13 is a front view thereof;

FIG. 14 is a rear view thereof;

FIG. 15 is a left side view thereof;

FIG. 16 is a ride side view thereof;

FIG. 17 is a top view thereof;

FIG. 18 is a bottom view thereof;

FIG. 19 is a front perspective view of the sofa component of the sofa, swivel chair, and chair set of FIG. 1, shown separately to reveal aspects of the design that may not be apparent in other views;

FIG. 20 is a rear perspective view thereof;

FIG. 21 is a front view thereof;

FIG. 22 is a rear view thereof;

FIG. 23 is a left side view thereof;

FIG. 24 is a right side view thereof;

FIG. 25 is a top view thereof; and,
FIG. 26 is a bottom view thereof.
